UNITED STATES PATENT OFFICE.

WILLIAM GAMBREL, OF LINCOLN, ILLINOIS.

DESIGN FOR A SALT-BOX.

SPECIFICATION forming part of Design No. 33,472, dated October 30, 1900.

Application filed June 19, 1900. Serial No. 20,902. Term of patent 14 years.

To all whom it may concern:

Be it known that I, WILLIAM GAMBREL, a citizen of the United States, residing at Lincoln, in the county of Logan and State of Illinois, have invented and produced a new and original Design for a Salt-Box, of which the following is a specification.

The invention relates to a new and original design for a salt-box; and it has for its object to provide a design of this character which will be both ornamental and useful.

The leading feature consists in the design forming the subject-matter of the accompanying illustration.

In the drawings, Figure 1 is a perspective view of a salt-box, showing my new and original design. Fig. 2 is a vertical sectional view. Fig. 3 is a reverse plan view.

Referring to the drawings, 1 designates an approximately semicylindrical salt-receptacle open at the top and back and composed of a solid horizontal bottom 2 and a solid continuously-curved wall 3, forming the front and sides of the receptacle. The bottom is provided with the straight rear edge, and it has at the center thereof a depending ear provided with an opening. The front and side edges of the bottom are continuously curved, the front being slightly flattened, and the walls 3 of the receptacle or box have their top and bottom edges of slightly different shape

and are provided with vertical rear edges located in the same vertical plane as the straight edge of the bottom of the box or receptacle. A pair of horizontal ears 5 project laterally from the upper ends of the straight edges of the wall 3, and they are disposed in the same vertical plane as the depending centrally-arranged ear 4. The lower edge of the curved wall conforms to the configuration of the curved edge of the bottom of the receptacle, and the said front and sides formed by the continuous wall are slightly flared or inclined and extend upward and outward at the sides of the box or receptacle, as clearly indicated in Fig. 3 of the accompanying drawings, and this flare or inclination gradually increases toward the center of the front, and the upper and lower edges of the continuous curved wall when viewed in reverse plan view converge from the center to the ends.

What I claim is—

The design for a salt-box herein shown and described.

In testimony that I claim the foregoing as my own I have hereto affixed my signature in the presence of two witnesses.

WILLIAM GAMBREL.
